LOADING AND PACKAGING DEVICE

Morris Matsen, Wilmington, Del., and Earl R. Jones, Philadelphia, Pa., assignors to E. I. du Pont de Nemours & Company, Wilmington, Del., a corporation of Delaware

Application December 22, 1944, Serial No. 569,342

7 Claims. (Cl. 249—55)

1

This invention relates to loading and packaging devices, and especially to devices for depositing elongated objects in an ordered arrangement in predetermined amount for packaging.

It is among the objects of the present invention to provide a continuously operating device for depositing a collection of objects in ordered arrangement. Another object is to provide for uniformly collecting together predetermined amounts of such objects in ordered arrangement. Other objects of the invention will be apparent from the following description and from the drawings constituting a part hereof in which

Fig. 1 is a view of the device partially in side elevation with parts broken away and partially diagrammatic,

Fig. 2 is a top plan view of the loading table with parts broken away showing driving devices therefor and a modified manner of mounting the pilot switch operator and cam drive.

Fig. 3 is an end view of the cam operated main switch showing a portion of its enclosing casing cut away,

Fig. 4 is a partial bottom view of the commutator.

Fig. 5 is a partial cross sectional view of the turn table and commutator, the section through the commutator being taken along the line 5—5 of Fig. 4, also showing diagrammatically the electrical circuits and the means for operating the pilot circuit,

Fig. 6 is a top plan view of the bag holder and load arm,

Fig. 7 is a side elevational view of the bag holder and load arm showing a partial cross sectional view of the turn table, and

Fig. 8 is a perspective view showing the arrangement of the receivers for orienting the materials.

Referring to Fig. 1, the device comprises in general the orienting receiver which is generally designated by A, a loading table 20 and a temporary depository which is generally designated by C. The receiver A which is normally closed, operates to receive the objects to be deposited, orient them in the position to be deposited and then open to discharge the objects in response to the advance of a succeeding advancing object. The discharging of the object is effected a period of time before the succeeding object advances for allowing the receiver to return to its normally closed position. The loading table 20, which is stationary during the loading thereof, receives the oriented objects which pass thereto from receiver A by gravity. The loading table

2

remains stationary until it has collected a predetermined weight of the objects and then is turned by weight controlled means until a new loading station is in position to receive the objects. Interposed between the receiver A and the loading table 20 is the temporary depository generally designated by C, which is normally open when the loading table is stationary so that the oriented objects will pass therethrough without interruption, but when the loading table is being turned to a new loading station the temporary depository is closed and retains the oriented objects as they are discharged from the receiver A. When a new loading station is reached, the temporary depository C is opened and returned to its normal position thereby discharging its deposit of oriented objects onto the loading table.

The invention is illustrated in connection with a cutting device comprising driven cutter wheels 1 carrying the knives B. The cutting device is adapted to cut off predetermined lengths of a continuously advancing thread, rope or ribbon 2 of material such as plastic material or rubber, thereby providing the receiver with a supply of elongated objects or lengths of material to be deposited or packaged. For this purpose, a receiver cam 3 is attached to the shaft of the upper driven cutter wheel 1 and is shaped to pass through one complete cycle with each cutting operation so that whenever material is fed to the cutter each cycle of the cam represents the delivery of one elongated object to the receiver. One end of a bell crank 4 which is pivoted on the pin 5 acts as a slider on the cam, and the slider is held on the fixed cam by the coil spring 6 which is biased against the other end of the crank. At the end of the bell crank 4 is a pivot or eye member 7 through which the thrust member 8 is passed. The two arms 8 of the thrust member are journaled at their ends on pins 9 which are secured to the outer ends of the cranks 10. The cranks 10 are secured to the outer ends of shafts 11 which are mounted at both ends to turn in the bearings 12 which are integral with the casing 13 as shown in Fig. 8. The bearings are mounted on a fixed support such as the walls of the casing 13. On the shafts 11 are mounted the leaves 18 of the receiver which are extended to contact at their inner edges and form a V-shaped bottom for the receiver when they are in normal closed position. The operating cam 3 is set so that when an elongated object is delivered to the receiver, the leaves 18 of the receiver are closed so that the elongated object will come to rest with its longitudinal axis parallel

with the line of contact of the V-shaped bottom of the receiver, thus locating the object in the desired fixed position for delivery to the loading table.

During the approach of a second elongated object, the indexing means, such as the driven cutter 1 which operates the cam 3, causes the cam 3 to turn through one operating cycle during the passage of the object, thereby operating bell crank 4, raising thrust rods 8 and opening the bottom of the receiver for discharging the object onto the receiving table B. The cam 3 is so proportioned that the bell crank 4, thrust rods 8 and bottom members 18 will be returned to normal or closed position before a succeeding object has been advanced to a point where it may be discharged into the receiver.

The elongated objects delivered to the receiver A are thus successively discharged in a fixed horizontal position and are received by the loading table 20. The loading table 20 preferably comprises a horizontal circular platform which is supported at its center to turn on ball bearings 14 which are mounted in the pedestal 21. A turret shaft 22 is provided for revolving the table into loading positions and retaining the table in such position until the predetermined load of delivered objects is collected. The upper end of shaft 22 is fixed to the table and the lower end carries a circular plate 15 upon which a number of cam rollers or followers 16 are mounted for engaging the groove in the cam 112. At its lower end, the shaft 22 turns in the bearing 17 which is attached to the pedestal 21 above the plate 15. There are as many rollers 16 on the plate 15 as there are loading stations on the table 20.

Rectangular openings 23 near the outer circumferential margin of the table 20 are provided at predetermined loading stations. The loading table is normally at rest with a loading station or opening 23 located directly under the receiver A so that the oriented elongated objects will fall therethrough by gravity as they are successively discharged by the receiver A. Bags or packaging containers 24 are suspended directly under the openings 23 on hooks 26 or other releasable attaching means to secure the bags in place during loading and permit the removal of a bag when it is loaded and moved out of loading position.

As shown in Figs. 6 and 7, a desirable bag retainer may comprise a band 25 enclosing a rectangular opening sufficient to provide a free opening into the bag at least as large as the opening 23 in the turn table. The band 25 is provided with any convenient means for attaching the bag or packaging container to the band 25, such as hooks 26.

The bag retainer is suspended on pins or trunnions 30 on opposite sides of the rectangular scale arm 31. The scale arm 31 is shaped to permit a free space below the opening 23 and is pivoted at its outer end on a pin 32 which is passed through brackets 33 on the under side of the table 20. At its inner end, the scale arm 31 has a triangular extension 35 having an opening 36 through which the bolt 37 freely passes permitting free vertical movement of the scale arm. The bolt 37 carries a load control spring 39 which engages the under side of the scale arm 31. The spring 39 is retained on the bolt 37 within a cup 40 which is retained on the bolt 37 by the nut 41. By screwing the nut 41 inwardly, the spring is adjustably biased against the scale arm for retaining the arm 31 in loading position until the bag is loaded with a desired weight of

objects to be packaged, whereupon the scale arm is depressed against the spring 39. At the inner end of the triangular extension 35 of the scale arm 31 is a contact member 42 which contacts 5 with and depresses the plunger 43 for closing the plunger operated switch 44, such as a "micro-switch," when the bag 24 is fully loaded and the scale arm 31 is fully depressed.

The switch 44 is mounted on a ring shaped part 10 150 composed of insulating material which is mounted underneath the turn table 20 on brackets 151 so that the ring will turn with the turn table. The ring 150 carries pairs of contacts 53 and 56 as shown in Figs. 1, 4 and 5 which are connected to opposite terminals of switch 44 through leads 54 and 55. There are as many assemblies of contacts 53 and 56, switch 44 and connections 54 and 55 as there are loading stations or openings in the turn table 20. Brushes 20 52 and 57 are mounted on insulation 52a on the stationary bracket 152 which is attached to the pedestal housing 21. The bracket 152 is desirably a circular plate having an outer marginal upturned flange which serves as a support at or 25 near the outer edge of the commutator plate 150 and in sliding engagement therewith. This upturned edge or rim also acts to avoid the accumulation of dust and dirt in and around the contacts. The brushes 52 and 57 are located so that the 30 opening 23 in the turn table 20 will be directly under hoppers A and C, and in loading position when contacts 53 and 56 are in contact with the brushes 52 and 57. The brushes 52 and 57 are suitably insulated from the bracket member 152. 35 Brush 52 is directly connected to line 50 through lead 51 and brush 57 is connected to one side of the rectifier R₁ through lead 54a.

When the switch 44 is closed by loading the bag and depressing scale arm 31, plunger contact 40 member 42 and plunger 43, a circuit from the main line 50 is established through lead 51, brush 52, lead 54, switch 44, lead 55, contact member 56, brush 57 and lead 54a, to the rectifier R₁, lead 63, coil 62, lead 61 and from the opposite 45 terminal of rectifier R₁ to the other side 60 of the main supply line through lead 59. This operation is the first step in controlling the closing of the biparted bottom of the temporary depository C for receiving the objects aligned and 50 charged by the receiver A while the loading table is being turned to the next succeeding loading station. The rectifier R₁ thus being energized and the circuit through line 61, to solenoid 62 and lead 63 being completed, the solenoid-controlled 55 retractable switch S thereupon closes across contact points 65 and 66. This action closes the circuit from power line 50 through leads 98, contacts 65 and 66, solenoid R, leads 71, 72 and resistor 73 to the other side 60 of the power line.

Energization of solenoid R operates the retractable switch T to close the circuit from main line 50 through lead 98, contacts 75 and 76, lead 78, solenoid 79, lead 80, contacts 81 and 82, and 65 leads 83 and 84 to the outside of resistor 73 and to the opposite side 60 of the power line. The consequent energizing of solenoid 79 draws the armature 85 of solenoid 79 inwardly, thereby 70 retracting tension rods 86 and levers 87 which turn the shafts 87a. The leaves 88 which form the biparted V-shaped bottom of the temporary depository C are attached to the shafts 87a and the operation closes the leaves to form the V-shaped bottom for retaining the objects delivered by the receiver A during the operation of 75

turning the loading table to the next succeeding loading station. The shafts 87a are mounted in the bearings 12 which are similar to the mountings of the shafts 11.

As solenoid switch T closes the circuit across contact point 75-76 and 81-82, it also closes the contact points 90-91 and 92-93 in the circuit of the clutch solenoid 94 which, upon being energized by current from the rectifier R₂, which is connected to the main line through leads 84 and 98, causes the clutch plates 95 and 96 to move into frictional engagement. The clutch plate 96 is constantly driven by the motor 97 which receives its power from the main power supply line through leads 84 and 98.

The revolving clutch plate 96 being engaged with plate 95 turns the table 20 through the turret shaft 22 which is provided at its lower end with a plate 15 upon which are mounted the followers 16. The followers 16 are equal in number to the stations 23 of the table 20 and they are spaced on the plate 15 so that a follower will always be engaged by the groove of cam 112. The cam 112 is operated through the train consisting of shaft 113, meshing gears 114 and 115 and shaft 116 which is attached to the driven clutch plate 95.

Cam switch 69 is operated by the cam 120 which is mounted on shaft 119. This shaft rotates integrally with the cam 112 which is driven by the clutch plate 95 through gears 114 and 115. Cam 120 is disposed so that cam switch 69 is normally open when the turn table is at rest and is disposed at a loading station under the hopper A. The open position of the cam switch and the disposition of the cam 120 for open position of the cam switch 69 indicates a loading station for a bag 24. Accordingly the groove of the turret cam 112 is given a pitch so that one complete revolution of turret cam 112 and the direct connected cam 120 will turn the turret shaft 22 and turn table 20 through exactly one loading station, the pitch of cam 112 depending upon the number of loading stations on the table 20. As shown in Figs. 2 and 3, the cam switch 69 and cam 120 are mounted on the base 21a of the pedestal 21 and are enclosed by a cover plate 21b.

When the turn table 20 is at rest and at a loading station, all circuits connected to the power lines 50 and 60 are open, except the connection to the constantly running motor 97 and to the rectifier R₂. In this position the solenoids 62, R, 79 and 94 are de-energized, the leaves 88 of retainer C are in open position, the clutch plates 95 and 96 are disengaged and switches S and T are retained open by retractors, such as springs which hold the switches open except when the solenoids 62 and R are energized.

When the predetermined load is delivered to the turn table, the loaded arm 31 is depressed against the spring 39, thereby closing the switch 44. The pilot circuit through lead 54a is thereby established to the rectifier R₁, switches S and T are closed to energize solenoids 79 and 94, and cam switch 69 is open. Operating cam 120 is so shaped that the cam switch will displace the rider 121 to close cam switch 69 as soon as the turn table has been turned through a small angle, say 1 or 2 degrees which is determined by the angular displacement necessary to move contacts 53 and 56 on the commutator 150 out of contact with brushes 52 and 57. The cam 120 is shaped to close switch 69 just before the pilot circuit opens. Cam 120 is also shaped so that the rider 121 will remain depressed and cam switch 69 will remain closed until table 20 has been turned to the next

succeeding loading station and the next succeeding pair of contacts 53 and 56 are in contact with the brushes 52 and 57, whereupon the cam 120 releases without any delay the spring biased 5 rider and switch operator 121 of cam switch 69 thereby breaking the circuit then established to rectifier R₁ from power line 50 through leads 98, 70, switch 69, lead 68, R₁, lead 72 and resistance 73 to power line 60. The pilot circuit through 10 switch 44 and lead 54a being open, solenoid 62 is de-energized and the spring switch S is permitted to return to open position thereby de-energizing solenoid R and permitting the spring controlled switch T to open. This results in de-energizing solenoids 79 and 94, the disengagement 15 of clutch plates 95 and 96, and the opening of leaves 88 of the hopper C.

At the start of the movement of the turn table which moves into a new loading position and after 20 switch 44 is closed by the load arm 31, the power is delivered to the rectifier R₁ through lead 51, brush 52, commutator contact 53 and lead 54, switch 44, lead 55, contact 56, brush 57 and lead 54a, and the return connection from the other side of R₁ is through lead 59 to line 60. This pilot circuit is retained only temporarily or until the cam 120 has closed cam switch 69 and the circuit through brushes 52 and 57 is opened by movement of the turn table which carries contact 25 members 53 and 56 out of their contact position with 52 and 57. Accordingly the commutator 150 is a ring of insulating material mounted on brackets 151 on the under side of table 20 and the commutator contact members 53 and 56 are 30 bolts, the enlarged heads of which set flush into the lower surface of the ring of insulating material 150. The contact members 53 and 56 are only large enough to remain in contact with the brushes 52 and 57 while the turn table 20 is at 35 rest at a loading station and thereafter until cam 120 has closed switch 69 and the turn table 20 is being turned a few degrees after it has started to turn into a new loading position. Thereafter the succeeding set of commutator contact members 53 and 56 is located so that full contact will 40 be established with the brushes 52 and 57 after the loaded beam 31 and bag 24 have moved out of engagement with the switch plunger 43, so that when the next succeeding loading station is in 45 position the pilot circuit will be open through switch 44 during the last few degrees of travel of the table by reason of the unloaded position of the beam 31 and switch plunger. When the table 20 reaches the next succeeding loading station 50 and the cam switch is suddenly released to open position by the cam 120, both the pilot circuit through the switch 44 and the main circuit through cam switch 69 to rectifier R₁ will be 55 opened. As a consequence thereof, the circuits 60 supplying power to solenoids 79 and 94 will be opened, the table will come to rest at the new loading station and the leaves 88 of the hopper C will discharge their accumulated load to bag 24. Thus the system will be restored to normal 65 loading operation.

Thus during the time that the table 20 is being 70 turned from one loading station to the next succeeding loading station and cam switch 69 is being retained in closed position by the cam 120, the power to energize the solenoid 79 for hopper C, rectifier R₁ and solenoid R is supplied by leads 98 from one side 50 of the power line and the return circuit is from the other side of solenoid 79 through leads 80 and 84 to 60, from the other 75 side of R₁ through lead 72 and resistance 73 to 60

and from solenoid R through lead 72 and resistance 73 to 60. While these circuits are established, the solenoid operated switch T maintains the circuit of rectifier R₂ closed for energizing the clutch solenoid 94, thereby engaging the clutch plates 95 and 96 and establishing the described mechanical connection from constantly running motor 97 to the spindle 22 for turning the table 20 toward the new loading position.

The present invention provides a device which satisfactorily loads objects into containers, such as bags and boxes in regular arrangement and in predetermined weight. The device operates to complete the routine acts involved in the packaging or loading operation without the necessity of personal attention except to remove the loaded receptacles and place unloaded receptacles in place. Various features of the device shown in the drawings and specifically described may be varied to suit the use, such as the form of the load control arm and the accommodation for retaining the receptacle in loading position, the mechanism for opening and closing the hopper A and various details of the device.

It will be recognized from the foregoing description that still other modifications can be made without departing from the invention, and it is to be understood that the present invention is not restricted to the specific illustration thereof which is set forth herein.

We claim:

1. A loading device which comprises a receiver for receiving elongated objects delivered thereto; said receiver having means for individually arranging the objects in predetermined alignment as they are delivered thereto; means for discharging each aligned object after it is aligned for loading it into a packaging receptacle; a carrier for supporting a plurality of packaging receptacles; means on the carrier for positioning a receptacle under the receiver in loading position, retaining it in loading position until a predetermined load is packaged therein and then moving another receptacle into loading position; said means comprising an electrical circuit connected to a source of power and a load actuated pilot switch in the circuit, said switch being actuated to close when a predetermined load is delivered to the receptacle, a motor for moving the carrier and receptacles into and out of the loading position when said switch means is actuated, means operated when said switch means is actuated for establishing an operative connection between the motor and carrier, and means operated by said motor for discontinuing said operative connection when an unloaded receptacle is brought into the loading position; collecting means between said receiver and said receptacle for retaining the aligned objects discharged from said receiver while an unloaded receptacle is being brought into loading position, and means controlled by said positioning means for maintaining said collecting means in retaining position while a receptacle is being moved into loading position.

2. A loading device which comprises a carrier having a plurality of loading positions; a load arm attached to the carrier having means for carrying a receptacle to be loaded with objects to be packaged; a pilot circuit connected to a source of power; a pilot switch in the pilot circuit; load responsive means depending on the load arm for actuating the pilot switch into closed position when a predetermined load is deposited in the receptacle; a constantly running driving motor connected to the source of power; said motor

having a clutch; a connection for operatively connecting the motor and carrier, thereby to move the carrier from one loading position to the next; an intermediate collecting means adapted to close and retain objects delivered when a receptacle is out of loading position; control means actuated by the closing of said pilot switch for retaining said clutch and the intermediate collecting means in closed position during said movement of the carrier; a control switch in a circuit connecting a source of power and said control means; means driven by said motor for retaining said control switch in closed position while a receptacle is being moved into loading position and for opening the switch when a loading position is reached, thereby permitting said clutch and intermediate collecting means to open.

3. A device in accordance with claim 1 in which the means on the carrier comprises a load arm attached to the carrier which actuates the pilot switch into closed position for closing a circuit from a power source when a package is loaded, the motor is constantly running, and the means for operatively connecting the motor and the carrier for moving the carrier from one loading position to the next comprises a magnetic switch; and the means on the carrier for positioning a receptacle under a receiver comprises a rotatable spindle upon which the carrier is mounted, and means connecting the spindle and motor for causing the spindle to revolve for moving a receptacle into loading position.

4. In a device in accordance with claim 1 wherein the carrier is a circular disc mounted to turn on a central upright spindle and the means for establishing an operative connection between the motor and carrier comprises a magnetic clutch and a switch cam driven by said motor, said disc having openings through which aligned objects are passed into the packaging receptacle, a driving cam for operating said upright spindle, means for driving the cam when the clutch is closed, a main switch, said switch cam being operatively connected with said driving cam and being shaped to close the power circuit through the main switch after a loaded receptacle has started to move out of loading position and to open said power circuit when the carrier has moved to the next succeeding loading position said operative connection comprising; a commutator on said carrier having pairs of contacts corresponding to each loading position; connections between said contacts and the opposite terminals of the pilot switch; a pair of stationary brushes mounted for contacting said contacts when a receptacle is in loading position, said brushes being connected to the opposite terminals of a power source; said pairs of contacts and brushes being formed to retain contact with each other after the carrier has started to move into a new loading position but to open the power circuit through the pilot switch before the carrier is moved into an unloaded position.

5. A loading device which comprises a receiver having a bottom portion shaped for orienting elongated objects which are delivered thereto; an indexing means for closing the bottom of said receiver before an object is delivered thereto and for opening said bottom for discharging the object after it is oriented; means for supporting a plurality of receptacles in succession underneath said receiver at a predetermined loading station; a pilot circuit, a normally open pilot switch in said circuit; a pilot circuit closing device on said supporting means operative for closing said normally

open pilot switch when a receptacle is loaded with a predetermined weight; means comprising a cam for moving a loaded receptacle from a loading position and for bringing another receptacle into a loading position; a motor; a solenoid operated clutch between said motor and cam; a normally open circuit comprising a rectifier connected to said solenoid; means actuated by said pilot circuit for closing the circuit to said solenoid for mechanically operating said cam from said motor.

6. A loading device which comprises a receiver having a bottom portion shaped for orienting elongated objects which are delivered thereto; an indexing means for closing the bottom of said receiver before an object is delivered thereto and for opening said bottom for discharging the object after it is oriented; means for supporting a plurality of receptacles in succession underneath said receiver at a predetermined loading station; a pilot circuit; a circuit closing device on said supporting means operative for closing said pilot circuit when a receptacle is loaded with a predetermined weight; a movable contact member in said pilot circuit associated with said receptacle support; a fixed contact member in said pilot circuit normally contacting with said movable contact when the receptacle is unloaded and is in unloaded position; means comprising a cam for moving a loaded receptacle from a loading position and for bringing another receptacle into loading position; a motor; a solenoid operated clutch between said motor and cam; a normally open circuit comprising a rectifier connected to said solenoid; means actuated by said pilot circuit for closing the circuit to said solenoid for mechanically operating said cam from said motor; a normally open main switch adapted to connect the said rectifier with the power circuit; means for closing said main switch after the loaded receptacle starts to move from loading position and for permitting it to open when an unloaded receptacle is moved into loading position; the contact of said movable and fixed contacts in the pilot circuit being broken after the main switch is closed.

7. A loading device which comprises a pedestal; a rotatable table supported by said pedestal having openings therein; a motor and means for operatively connecting the motor and table; means for suspending a packaging receptacle

beneath each of said openings in the table comprising scale arms to which said receptacles are attached, said scale arms being carried by said table and being mounted to rotate therewith; a pilot circuit connected to a source of power; a normally open pilot switch in said circuit; means on said scale arms for operating the pilot switch when a scale arm and its attached receptacle are in loading position and the receptacle is loaded; a pair of movable contact members which are carried by said table and are normally in said pilot circuit when a receptacle is in loading position; a pair of fixed contact members carried by said pedestal normally in said pilot circuit 15 when a receptacle is in loading position; a normally open motor circuit connecting the motor and a source of power; means for temporarily interrupting the delivery of objects to packaging receptacles when an unloaded receptacle is being brought into loading position; electro-magnetic means for operating said temporary interrupting means; a circuit for connecting said electro-magnetically operated means to a source of power; and means activated when the pilot switch is 20 closed for closing the motor circuit and the circuit to said electro-magnetically operated means; and means for opening said circuits when a receptacle is brought into loading position.
